(57) **CLAIM**

The ornamental design for a panel for banking equipment, as shown and described.

DESCRIPTION

FIG. 1 is a top, front perspective view of a panel for banking equipment showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions shown in broken lines in the drawings are not part of the claimed design.
